UNITED STATES PATENT OFFICE.

PERRY J. GARRISON, OF OXFORD, MICHIGAN.

MEANS FOR COOLING INTERNAL-COMBUSTION ENGINES.

1,396,953.

Specification of Letters Patent.

Patented Nov. 15, 1921.

Application filed September 22, 1919. Serial No. 325,321.

To all whom it may concern:
Be it known that I, PERRY J. GARRISON, a citizen of the United States, residing at Oxford, county of Oakland, State of Michigan, 5 have invented a certain new and useful Improvement in Means for Cooling Internal-Combustion Engines, and declare the following to be a full, clear, and exact description of the same, such as will enable others 10 skilled in the art to which it pertains to make and use the same, reference being had to the accompanying drawings, which form a part of this specification.

My invention relates to means for cooling 15 internal combustion engines and for supplying the carbureter with moistened air free from dust or dirt, that its efficiency may be increased.

One object of the present invention is to 20 dispense with the usual radiator employing a plurality of thin metal tubes through which water from the water jacket of the engine circulates that the water may be cooled before returning it again to the engine,—and 25 also to dispense with the usual fan employed to insure the passage of air around the tubes to assist the cooling action.

One feature of the present invention consists in a water chamber,—occupying the 30 same relative position as the usual radiator, said chamber containing a pipe opening at one end into the water pipe connection between the water chamber and the water jacket of the engine; the other open end of 35 the pipe extending through the wall of the chamber that air from the outside may be drawn through the pipe by the circulation of water through the water jacket,—that it may also assist in the cooling of the engine.

40 A further object is to supply moistened air to the carbureter by providing a connection between the carbureter and the water chamber above the water level in the latter, thus the suction stroke of the engine will 45 serve to deliver moistened air to the carbureter,—while the air drawn through the water operates to cool the latter as it circulates between the water chamber and the water jacket of the engine, the air in turn 50 being purified in its passage.

With the foregoing and other objects in view which will appear as the description proceeds, the invention resides in the combination and arrangement of parts and in the 55 details of construction hereinafter described and claimed, it being understood that

changes may be made in the precise embodiment of the invention within the scope of what is claimed without departing from the spirit of the same.

60 In the accompanying drawings:—

Figure 1 is a side elevation of an internal combustion engine showing the water chamber and connections between it and the water jacket of the engine and also with the carbureter.

65 Fig. 2 is a rear elevation of the water chamber with parts broken away and in section to more clearly disclose its construction.

Fig. 3 is a side elevation of the engine and 70 water chamber with parts in section, showing the connection between the water chamber and the water jacket of the engine as viewed from the side opposite that shown in Fig. 1.

75 Fig. 4 is a vertical cross-sectional view through the water chamber on or about line 4—4 of Fig. 2.

Fig. 5 is a horizontal cross-sectional view of the water chamber on or about line 5—5 80 of Fig. 2.

Referring now to the letters of reference placed upon the drawings:—

A, denotes an internal combustion engine. B, its water jacket. C, its intake manifold. 85 D, its exhaust manifold. E, a carbureter connected with the intake and exhaust manifolds and F, an exhaust pipe leading to a muffler (not shown).

G, designates the water chamber, preferably constructed of cast metal, divided adjacent to its lower end,—the lower portion being secured to the upper part by bolts g, extending through flanges formed on the upper and lower sections.

90 H, indicates a water pipe connection between the water jacket and the water chamber for returning the water to the latter and I, indicates a water pipe connection leading from the water chamber to the water jacket.

J, denotes a U-shaped pipe lodged within the water chamber, its upper open ends projecting through the wall of the radiator to admit air to the pipe. K, indicates a pipe 100 connection between the U-shaped pipe and opening within the water pipe connection I, leading from the water chamber back to the engine. L, is a filler cap, by removing which the chamber G, may be filled with water. 105 M, is a pipe connection between the water chamber above the water level therein and

the usual air inlet to the carbureter. N, is a fuel pipe leading to the carbureter under control of a suitable valve N'. The carbureter shown forms no part of the present invention but is the subject matter of another application and it will therefore require no detailed description here, as any suitable carbureter may be employed in connection with the water chamber.

10 Upon the engine operating under its own power, its suction stroke will draw air from the water chamber G into the carbureter thus creating a partial vacuum in the water chamber above the water level therein;—
15 the water in the pipe J being immediately forced out of said pipe by atmospheric pressure, air thereafter being delivered through said pipe due to the combined action of atmospheric pressure and the circulation of water between the water jacket and the water chamber.

In the winter during freezing weather, water may be eliminated entirely as the cooling action of the air drawn through the chamber and water jacket of the engine will be found sufficient for all purposes.

What I claim is:—

1. The combination with an internal combustion engine, of a water chamber, suitable pipe connections between the water chamber and the water jacket of the engine to provide for a circulation of water therethrough, and a pipe having an open end sleeved within the water return connection between the water tank and the water jacket of the engine, the other end of the pipe being open to the outer air to admit the air therethrough into said water pipe connection and thence to the water jacket of the engine.
- 20 2. The combination with an internal combustion engine and a carbureter connected with its intake manifold, of a chamber, suitable pipe connections between the chamber and the water jacket of the engine, a pipe connecting the chamber with the air intake to the carbureter, and a pipe having an open end sleeved within the return connection between the chamber and the water jacket of the engine, the other end of the

pipe being open to atmosphere, whereby air 50 may be drawn through the pipe from the outer atmosphere through the water jacket of the engine, to cool the water in said jacket.

3. The combination with an internal combustion engine and a carbureter connected with its intake manifold, of a water chamber, suitable pipe connections between the water chamber and the water jacket of the engine, a pipe connecting the water chamber 60 above the water level in the latter with the air intake to the carbureter, a U-shaped pipe within the water chamber with its open ends projecting through the wall of the water chamber to admit air into said pipe, and an 65 open ended pipe leading from said U-shaped pipe into the return water pipe connection between the water chamber and the water jacket of the engine, whereby the outer atmosphere may be drawn through the water 70 jacket of the engine to cool the water circulating through the latter.

4. The combination with an internal combustion engine and a carbureter connected with its intake manifold, of a cast metal water 75 chamber divided to admit of assembling suitable pipe fittings therein, a water pipe connection between the water jacket of the engine and the water chamber for the circulation of water therethrough, a pipe connecting the water chamber above its water level with the air intake to the carbureter, a pipe fitting lodged within the water chamber extending through the wall of the chamber and open for the admission of air to said 85 fitting and an open pipe connection extending from said fitting to and projecting within the said water pipe return between the water chamber and the water jacket of the engine, whereby the outer air may be drawn 90 through the water jacket of the engine.

In testimony whereof, I sign this specification in the presence of two witnesses.

PERRY J. GARRISON.
